DESIGN FOR A TABLE

Viktor Harasty, Whitestone, N. Y.

Application February 5, 1944, Serial No. 112,459

Term of patent 7 years

(Cl. D33—14)

To all whom it may concern,

Be it known that I, Viktor Harasty, a stateless citizen who has his first papers, residing in Whitestone, in the county of Queens and State of New York, have invented a new, original, and ornamental Design for a Table, of which the following is a specification, reference being had to the accompanying drawing, forming part thereof.

In the drawing:

Fig. 1 is a perspective view of a table, showing my new design.

Fig. 2 is a top plan view thereof.

I claim:

The ornamental design for a table, as shown.

VIKTOR HARASTY.
